[57] CLAIM

The ornamental design for a table-top easel, as shown and described.

DESCRIPTION

FIG. 1 is a front, left side perspective view of a table-top easel showing my new design;

FIG. 2 is a right side elevational view thereof, the left side elevational view being a mirror image;

FIG. 3 is a top plan view thereof;

FIG. 4 is a front elevational view thereof;

FIG. 5 is a bottom plan view thereof;

FIG. 6 is a front, left side perspective view of an alternate embodiment of FIG. 1;

FIG. 7 is a right side elevational view of FIG. 6, the left side elevational view being a mirror image;

FIG. 8 is a top plan view of FIG. 6;

FIG. 9 is a front elevational view of FIG. 6; and

FIG. 10 is a bottom plan view of FIG. 6.
